(57) CLAIM

The ornamental design for a medical pump as shown and described.

DESCRIPTION

The patent or application file contains at least one drawing executed in color. Copies of this patent or patent application publication with color drawing(s) will be provided by the Office upon request and payment of the necessary fee.

1. Medical pump
2. Medical pump
- 1.1 : Front
- 1.2 : Rear
- 1.3 : Left
- 1.4 : Right
- 1.5 : Top
- 1.6 : Bottom
- 1.7 : Top, Front, Left Perspective
- 1.8 : Top, Rear, Left Perspective
- 1.9 : Top, Front, Right Perspective
- 1.10 : Top, Rear, Right Perspective
- 2.1 : Front
- 2.2 : Rear
- 2.3 : Left
- 2.4 : Right
- 2.5 : Top
- 2.6 : Bottom
- 2.7 : Top, Front, Left Perspective
- 2.8 : Top Rear, Left Perspective
- 2.9 : Top, Front, Right Perspective
- 2.10 : Top, Rear, Right Perspective

1 Claim, 20 Drawing Sheets
